US0D1080639S

(12) **United States Design Patent** (10) Patent No.: **US D1,080,639 S**
 Dalsania et al. (45) Date of Patent: ** Jun. 24, 2025

(54) **DISPLAY SCREEN OR PORTION THEREOF WITH GRAPHICAL USER INTERFACE**

(71) Applicant: SAP SE, Walldorf (DE)

(72) Inventors: **Sona Dalsania**, Bengaluru (IN);
Krishnan Vijayaraghavan, Bengaluru (IN)

(73) Assignee: SAP SE, Walldorf (DE)

(**) Term: **15 Years**

(21) Appl. No.: **29/795,071**

(22) Filed: **Jun. 16, 2021**

(51) LOC (15) Cl. **14-04**

(52) U.S. Cl.

USPC **D14/485**; D14/487

(58) **Field of Classification Search**

USPC D14/485-495

CPC G06F 3/048-04897

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
